The ornamental design for a faucet, as shown and described.

DESCRIPTION

In a preferred embodiment, the nature of this product is as a plumbing fixture in the form of a faucet for washing various items and/or body parts.

FIG. 1 is a right, top, front perspective view of a faucet embodying my new design;

FIG. 2 is a right side elevational view thereof;

FIG. 3 front elevational view thereof;

FIG. 4 is a rear elevational view thereof;

FIG. 5 is a left side elevational view thereof;

FIG. 6 is a top plan view thereof;

FIG. 7 is a bottom plan view thereof; and,

FIG. 8 is a left, top front perspective view of a faucet according to another embodiment of my new design, the left side, front, rear and right side elevational views thereof being mirror images of respective FIGS. 2-5 and the top and bottom plan views thereof being mirror images of respective FIGS. 6 and 7.

The broken line representation of openings in FIG. 7 is for the purpose of illustration only, and form no part of the claimed design.
